UNITED STATES PATENT OFFICE.

FRANK O. HELLSTROM, OF GROVE, NORTH DAKOTA.

RAIL-SUPPORT.

1,054,768.

Specification of Letters Patent.

Patented Mar. 4, 1913.

Application filed October 25, 1912. Serial No. 727,802.

To all whom it may concern:

Be it known that I, FRANK O. HELLSTROM, a citizen of the United States, residing at Grove, in the county of Burleigh and State 5 of North Dakota, have invented a new and useful Rail-Support, of which the following is a specification.

The device constituting the subject matter 10 of this application is a composite rail support.

The invention aims to provide novel means for connecting the rail holding members which are embedded in the body portion of the support; and to provide novel 15 means for holding the said members in place in the body.

Another object of the invention is to provide rail braces of novel form and to provide novel means whereby the same may be 20 connected with a member which is embedded partially in the body portion of the support.

Another object of the invention is to increase the utility of devices of that type to which the present invention appertains.

With the foregoing and other objects in view which will appear as the description proceeds, the invention resides in the combination and arrangement of parts and in the details of construction herein disclosed 25 30 can be made within the scope of what is claimed without departing from the spirit of the invention.

In the drawings:—Figure 1 is a side elevation; Fig. 2 is a transverse section on the line 2—2 of Fig. 1; Fig. 3 is a transverse section on the line 3—3 of Fig. 1; Fig. 4 is a longitudinal section on the line 4—4 of Fig. 3, the rail appearing in elevation; and Figs. 5 and 6 are sectional details enlarged, 35 respectively, from Figs. 3 and 2.

In carrying out the invention there is provided a base 1 which preferably is fashioned from concrete. The base 1 is provided in its upper face with a longitudinal groove 2, receiving a rail plate 3 which preferably is fashioned from wood, it being the intention that the base 1 shall extend longitudinally 45 of the rail 4, the rail 4 being immediately supported by the rail plate 3.

The invention further includes a pair of angle members, each angle member comprising a primary flange 5. The primary flanges 5 are embedded in the base 1 upon opposite sides of the rail plate 3. The primary flanges 5, up- 50 55 stand slightly above the upper face of the base 1. The angle members include second-

ary flanges 6 and 7, denoted by separate reference characters for convenience in description. The secondary flange 6 of one angle member extends toward the longitudinal center of the base 1, the secondary flange 7 of the other angle member extending away from the longitudinal center of the base. The secondary flange 6 overhangs the rail plate 3 and overhangs the flange of the rail 4, so as to hold the flange of the rail 4 down upon the rail plate 3 and to prevent the rail 4 from moving transversely of the base 1. The upper portion of that primary flange 5 which is connected with the secondary flange 7 constitutes an abutment for one edge of the flange of the rail 4, so as to maintain the other edge of the flange of the rail engaged beneath the secondary flange 6 of the opposite angle member.

Tubes 8 extend through the base 1 and through the flanges 5 of the angle members. The tubes 8 exercise four functions. First, they serve to reinforce the base 1; second, as they pass through the flanges 5 of the angles members, they constitute means for holding the angle members in the base 1; third, they serve to receive ties 9 whereby the base members may be connected transversely of the track; and fourth, they serve as abutments for nuts 10 which, being threaded upon the ties 9, permit the bases 1 to be moved longitudinally of the ties 9, thereby permitting the gage of the track to be changed. The members 10, further, serve 90 to maintain the rails 4 at a fixed distance apart.

The invention further includes braces 11. These braces 11, preferably, are located adjacent the ends of the rail 4. Each brace 11 terminates in an upstanding foot 12 abutting against the side face of the web of the rail 4, the foot 12 being attached to the web of the rail by means of securing elements 14. The brace 11 terminates in a hook 15 engaged around the secondary flange 7 of one angle member, as shown most clearly in Fig. 6. Securing elements 16 which may be rivets or the like, pass through the flange 7 and through the hook 15, to hold the braces 11 in place. Other braces 18 are provided, the braces 18 ordinarily being located, in any number, intermediate the ends of the rail 4. The braces 18 bear upon the upper face of the flange of the rail 4, the braces 18 being extended through openings 17 formed in the flange 5 of that angle member which is

provided with secondary flange 7. The braces 18 terminate in hooks 19 which extend upwardly around the flange 7, the hooks 19 being secured to the flange 7 by 5 means of attaching elements 20 which may be rivets or the like.

In practical operation, the rails 4 are strung along the track upon the outside thereof. The rails are then thrown inwardly by bars, or otherwise, until the flanges of the rails engage beneath the members 6, the flanges of the rails dropping down upon the rail plates 3. The rail braces 11 and 18 are then connected with the 10 secondary flange 7 through the medium of the securing elements 16 and 20, the securing elements 14 being mounted in place in the web of the rail 4 and in the feet 12 of the braces 11. Thereupon, the rails will be 15 held securely in place upon the bases 1. To change the gage of the track, it is necessary merely to manipulate the nuts 10.

Having thus described the invention, what is claimed is:—

25 1. A rail support comprising a base; angle members including primary flanges embedded in the base and secondary flanges extended in a common direction transversely of the base; and a rail brace connected with 30 one secondary flange.

35 2. A rail support comprising a base; angle members including primary flanges embedded in the base and secondary flanges, the secondary flange of one angle member 35 extending toward the longitudinal center of the base and the secondary flange of the other member extending away from its longitudinal center of the base; and a rail engaging element assembled with the last 40 specified flange.

45 3. A rail support comprising a base; angle members comprising primary flanges partially embedded in the base and secondary flanges extended in a common direction 45 transversely of the base; a portion of the primary flange of one angle member constituting an abutment to maintain the web of the rail beneath secondary flange of the other angle member; and a rail engaging 50 element assembled with the secondary flange of that angle member the primary flange of which constitutes an abutment.

55 4. A rail support comprising a base; angle members including primary flanges embedded in the base and secondary flanges extended in a common direction transversely of the base; and a rail holding element including a hook engaged with one secondary

flange; and means for securing the hook to 60 said secondary flange.

5. A rail support including a base; angle members including primary flanges embedded in the base and secondary flanges extended in a common direction transversely of the base, the primary flange of one angle member being provided with an opening; a rail holding element extended through the opening and provided with a hook engaging the secondary flange which is adjacent the opening; and means for connecting the hook 70 with said secondary flange.

6. A rail support including a base; angle members including primary flanges embedded in the base and secondary flanges extended in a common direction transversely 75 of the base; a rail holding element superposed upon one secondary flange; and means for connecting the rail holding element with said secondary flange.

7. A rail support including a base; angle members including primary flanges embedded in the base and secondary flanges extended transversely of the base; the primary flange of one angle member being provided with an opening; a rail holding element 85 mounted in the opening and extended transversely of the adjacent secondary flange; and means for connecting the rail holding elements with said secondary flange.

8. A rail support including a base; angle 90 members including primary flanges embedded in the base and secondary flanges extended transversely of the base; a rail brace including a hook engaged with one secondary flange and an upstanding, rail engaging 95 foot; and means for securing the hook to said secondary flange.

9. A rail support including a base provided with a groove in its upper face; a rail plate resting in the groove; angle members 100 including primary flanges embedded in the base upon opposite sides of the rail plate and secondary flanges, one of which overhangs the rail plate, the other of which extends away from the rail plate; and a rail 105 engaging element connected with the secondary flange which extends away from the rail plate.

In testimony that I claim the foregoing as my own, I have hereto affixed my signature in the presence of two witnesses.

FRANK O. HELLSTROM.
